(57) **CLAIM**

The ornamental design for a tail light lens, as shown and described.

DESCRIPTION

FIG. 1 is a front, right side perspective view of a tail light lens, showing our new design.

FIG. 2 is a front, left side perspective view thereof.

FIG. 3 is a rear right side perspective view thereof.

FIG. 4 is a rear left side perspective view thereof.

FIG. 5 is a front elevation view thereof.

FIG. 6 is a rear elevation view thereof.

FIG. 7 is a right side elevation view thereof.

FIG. 8 is a left side elevation view thereof.

FIG. 9 is a top plan view thereof; and,

FIG. 10 is a front elevation view thereof, shown within an environment of use.

In FIG. 10, the broken lines depict boundaries and form no part of the claimed design. The depiction of a vehicle shown de-emphasized in half tones represents environmental subject matter that forms no part of the claimed design.

1 Claim, 10 Drawing Sheets
